UNITED STATES PATENT OFFICE

141,826

DESIGN FOR A HOT-AIR FURNACE

Roy E. Deming, Kalamazoo, Mich., assignor to
Kalamazoo Stove and Furnace Company, Kal-
amazoo, Mich., a corporation of Michigan

Application December 1, 1944, Serial No. 116,660

Term of patent 7 years

(Cl. D81—1)

To all whom it may concern:

Be it known that I, Roy E. Deming, a citizen of the United States, residing at Kalamazoo, in the county of Kalamazoo, State of Michigan, have invented a new, original, and ornamental Design for Hot-Air Furnaces, of which the following is a specification, reference being had to the accompanying drawing, forming part thereof.

Fig. 1 is a front elevational view of a hot-air furnace showing my new design, and

Fig. 2 is a sectional view taken on line 2—2 of Fig. 1 to show the cross-sectional shape.

The top and back portions of the furnace not shown are substantially plain.

I claim:

The ornamental design for a hot-air furnace, as shown and described.

ROY E. DEMING.
